UNITED STATES PATENT OFFICE.

HUGO R. SWANSON, OF BROOKLYN, AND KILIAEN M. VAN RENNSELAER, OF WOOD-MERE, NEW YORK, ASSIGNEES TO TRIANGLE KAPOK MACHINE CORPORATION, OF NEW YORK, N. Y., A CORPORATION OF DELAWARE.

MATTRESS-FILLER-TREATING MACHINE.

Application filed March 21, 1927. Serial No. 176,938

This invention relates broadly to fibre treating machines.

One of the objects of this invention is the provision of a novel form of aeration tank 5 for use in connection with fibre treating machines.

A still further object of this invention is the provision of an aeration tank which is adapted for cleaning cotton linters, kapok, 10 felt fibres and the like for removing dust and seeds therefrom.

Another object of this invention is the provision of a closed circulation system associated with the aeration tank to provide a 15 continuous path of movement for the material to be treated and means for delivering the material from the circuit without permitting the escape of dust from the aeration tank.

A still further object of this invention is 20 the provision of a delivery nozzle which does not pass through the aeration tank and which is arranged adjacent the feed point of the device so that a single machine may be operated by one man from a given point.

25 These and many other objects such as the rapidity of treatment of the material, efficiency of cleaning thereof, rapidity of filling mattresses after the material has been cleaned and operation with little waste of raw material.

30 This invention resides in the construction, combination, arrangement and relative location of parts as will be more fully pointed out hereinafter.

35 Referring to the drawings,

Figure 1 is a side elevational view of the device of this invention with a portion of the aeration tank broken away.

40 Fig. 2 is a top plan view of the device of this invention.

Fig. 3 is a cross sectional view with some 45 parts broken away, taken on the line 3—3 of Fig. 2.

Fig. 4 is a cross sectional view taken on the 50 line 4—4 of Fig. 3.

Fig. 5 is an enlarged side elevational view of the picker device.

Fig. 6 is a top plan view of the means for 55 operating the picker device.

Fig. 7 is a cross sectional view taken on the line 7—7 of Fig. 8; and,

Fig. 8 is a cross sectional view taken on the line 8—8 of Fig. 5.

The device of this invention is arranged for the treatment of cotton linters, down, kapok 55 and similar fibres.

A grating is provided at the base of the aeration tank through which the seeds may fall when kapok is being treated. A cover is provided for this grating to be placed thereover when other types of fibres are being treated. When a circulation system is interrupted to permit delivery of the fibres to the mattress filling nozzle, a back pressure is created in the aeration tank which has a tendency 60 to blow the dust therein into the surrounding atmosphere. The present form aeration tank has been modified so that this is prevented. All the parts to be controlled by an operator are arranged together so that 65 they may be supervised from a single point.

Referring to the drawings the aeration tank is shown comprising circular portions 1 and 3 connected by the tapering portion 2. A tapering portion 4 connects to the portion 75 1 and runs into the base portion 5. A removal pan 7 is provided in the base portion and has disposed above it and at an angle, the grating 6' upon which may be placed when desired, the cover member 6. A pipe or conduit 8 connects to the top of the aeration tank and at its bottom, is another conduit 9 which has a hopper or filling member 10 mounted thereon. The conduit 9 connects to the picker device 12 which is provided with a by-pass 80

17. From the picker device and the by-pass a conduit 13 extends to the blower 14 which has a delivery pipe 15 which is connected to the pipe 8. The inlet of the picker device is provided with a gate 16 (Fig. 7) which, 85 when in its upper position, closes off the by-pass and when in its lower position, opens the by-pass and closes the inlet to the picker. A similar gate 18 is shown in the pipe 15 which closes off the pipe 8 when in its upper 90 position, opening the pipe 15 to the nozzle 20. This gate is operated by means of the lever 21 which is connected to a foot lever 22. A spring 23 maintains the gate 18 in its lower position to cut off the nozzle but when the foot 95 lever 22 is depressed, pipe 8 is closed and the nozzle 20 is opened to pipe 15. A smaller conduit 24 is connected to the inlet of a smaller blower 25 which has a dust bag 26 connected to its outlet. An open ended chamber 27 is mounted on the top of the member

3 and connects to the pipe 24. The chamber 27 is open to the atmosphere at 28. A screen or perforated member 11 is provided in the top of the aeration tank. In Figure 3 it will be noted that conduit 8 is connected to the aeration tank below the screen 11, while the pipe 24 connects to the tank and chamber 27 above the perforated member 11. The picker device is driven by means of shaft 29 through the agency of the motor 25'. The picker member 30 is mounted on a shaft 29 and a cooperating member 31 is mounted on another shaft 29'. These two shafts are geared together by means of the gears 32 and 33 of different sizes so that the picker members operate at different speeds. The blower 14 is driven by means of the motor 14'.

The method of operation is as follows:

When kapok is to be treated, the grating 6' is uncovered by removal of the plate 6 and the kapok raw material is placed into the hopper 10. The two blowers are started in operation and the material is circulated through the pipe system and the aeration tank; the valve 18 being in its lowermost normal position. Valve 16 is in its lowermost position so that the kapok material does not pass through the picker which is not necessary for this type of material; as the raw material circulates through this system it is broken up and the seeds fall through the grating 6' and any dust and small particles are drawn through the screen 11 by means of the blower 25 into the dust bag 26. The mattress to be filled is placed over the nozzle 20 and the lever 22 is depressed which diverts the raw material to the nozzle 20. When the valve 18 closes the pipe 8, a back pressure is created in the aeration tank which would normally force or eject dust into the atmosphere but, due to the arrangement of the chamber 27, with its opening at a separated point from the place where the conduit 24 connects to the aeration tank, the dust is drawn through the pipe 24 before it can escape from the opening 28.

When other types of raw material are treated, the plate 6 is placed on the grating and gate 16 is raised so as to close the by-pass 17, thus causing the raw material to pass through the picker where it is broken up and separated. Otherwise, the operation of the machine is substantially as described above.

It will be apparent from the foregoing description that we have devised a new and novel combination of elements for treating raw fibre stock.

It will be apparent to those skilled in the art that many changes in the details of con-

struction and operation of the device will readily occur without departing from the spirit of our invention and we do not therefore desire to be limited except as required by our appended claims.

What we seek to secure by United States Letters Patent is:

1. In a machine of the character described the combination with an aeration tank, a circulatory system associated therewith and means for causing the material to be treated to circulate in said system of means communicating with said tank for removing the dust therefrom whenever a back pressure is created in said system.

2. In a machine of the type described the combination with an aeration tank, and an associated conduit system of a delivery nozzle, means for connecting said nozzle to said system and means for preventing the discharge of dust from said tank by the creation of a back pressure in said system when said nozzle is connected thereto.

3. In a system of the type described the combination with a closed aeration tank, a closed circulatory system connected to said tank and means for causing a circulating current in said system of means for delivering material from said system and means communicating with the top of said tank for suppressing back pressure in said tank when the circulating current is diverted to said delivery means.

4. The combination with a closed aeration tank having an inlet and outlet passage connected to a conduit system and suction means in said system of suction means connected to the top of said tank for suppressing back pressure when said inlet passage is closed for delivery operation.

5. In a system for treating fibers, the combination comprising a tank, a screen in said tank near the top, a circulatory system connected to said tank, one end delivering into said tank just below the screen, a blower connected into said system, a delivery nozzle, means for connecting said nozzle therein and means connecting with said tank above said screen for withdrawing dust from said tank caused by the back pressure built up when said nozzle is connected to said circulatory system, said screen acting to prevent the fibers from escaping from the tank.

In testimony whereof we have hereunto set our hands on this 17th day of March A. D., 1927.

HUGO R. SWANSON.
